United States Patent Office.

DAVID L. STILES, OF ROCHESTER, NEW YORK, ASSIGNOR TO AUGUSTA P. STILES, OF SAME PLACE.

Letters Patent No. 75,594, dated March 17, 1868.

IMPROVEMENT IN FIRE-POTS FOR STOVES.

The Schedule referred to in these Letters Patent and making part of the same.

TO ALL WHOM IT MAY CONCERN:

Be it known that I, DAVID L. STILES, of Rochester, in the county of Monroe, and State of New York, have invented a certain new and useful Improvement in Fire-Pots for Stoves; and I do hereby declare that the following is a full and exact description thereof, reference being had to the accompanying drawings, making part of this specification.

Figure 1 is a perspective view of my improved fire-pot.

Figure 2, a central vertical section.

Figure 3, a horizontal section.

Figure 4, a view of one of the staves.

Like letters of reference indicate corresponding parts in all the figures.

My invention consists in the combination, with a fire-pot constructed of iron staves fitting together, of longitudinal passages through the same, for the passage of air, and perforations, slots, or equivalent openings from said passages, through the whole inner surface of the fire-pot, for the introduction of the air to burn the gases, as hereinafter set forth.

In the drawings is shown the fire-pot, which is composed of a series of cast-iron staves, A A, fitting together, at top and bottom, in rings *a a* of the plates of the stove, as represented. These staves are so cast as to form longitudinal air-passages or grooves, *c c*, through the walls of the fire-pot, as most clearly shown in the cross-section, fig. 3. I prefer to cast a half groove in each side of a stave, as shown; but, if desired, the whole groove may be formed in the centre of each stave. These grooves extend from bottom to top of the fire-pot. From the grooves *c c* numerous perforations, slots, or equivalent passages, *ff*, open radially to the interior of the fire-pot, thus covering its whole inner surface with air-holes, as indicated.

This making of the fire-pot in staves, and the combination therewith of the air-passages and numerous perforations, not only secures simplicity in construction, but also secures a most complete combustion and burning of the gases, which usually escape. Whenever any portion of the fire-pot burns out it is easily replaced. The air-passages, however, in a great degree, prevent burning out, by keeping the staves cool. The contraction of the top of the fire-pot, as shown, causes the gases to pass slowly along the inner surface of the same, and, the air from the numerous perforations *ff* coming in contact therewith, supplies the necessary oxygen to produce a most perfect combustion. The great surface of the fire-pot occupied by the said perforations insures the supply of a continuous sheet of air.

It will be noticed that the casting of the staves is very readily accomplished so as to fit together and form both the passages *c* and perforations *f*. It is only necessary to cast grooves for the one and notches for the other, as shown in fig. 4.

By the means above described, it will be noticed that I allow the passage of air directly through the staves forming the walls of the fire-pot, whereby I not only simplify the construction, but also produce a greater heating-power by radiation directly from the body of the fire-pot without the interposition of a surrounding cylinder, as is required in all other stoves of this kind with which I am acquainted where air must be held to the body of the fire-pot to allow it to pass through holes in the sides. By passing the air directly through the staves themselves, I avoid the necessity of such a surrounding cylinder.

I do not claim simply forming a fire-pot of staves, nor simply air-passages and perforations in other relations, as I am aware that each has before been used separately; but

What I claim as my invention, and desire to secure by Letters Patent, is—

The combination, with a fire-pot formed of a series of staves, of passages formed in said staves, which will allow air to pass directly through the wall of the fire-pot from the base, as herein set forth.

I also claim, in combination with a fire-pot, made of a series of staves, and having air-passages passing directly through the walls of the fire-pot from the base, a series of perforations, slots, or equivalent passages, opening through the whole interior of the fire-pot to admit air to burn the gases, as herein set forth.

In witness whereof, I have hereunto signed my name in the presence of two subscribing witnesses.
